UNITED STATES PATENT OFFICE.

WILLIAM T. HAWKINS, OF ROCKAWAY, NEW JERSEY.

DISPENSING-PUMP.

1,289,752.

Specification of Letters Patent.

Patented Dec. 31, 1918.

Application filed December 14, 1916. Serial No. 137,007.

To all whom it may concern:

Be it known that I, WILLIAM T. HAWKINS, a citizen of the United States, residing at Rockaway, in the county of Morris and

5 State of New Jersey, have invented certain new and useful Improvements in Dispensing-Pumps; and I do hereby declare the following to be a full, clear, and exact description of the invention, such as will enable others skilled in the art to which it

10 appertains to make and use the same.

My invention relates to new and useful improvements in dispensing pump, and more particularly to that class adapted to

15 be used for dispensing gasolene and similar products, and my object is to provide a manually operated gear mechanism for operating the pump for dispensing or forcing a certain amount of gasolene or other fluid 20 through a discharge pipe.

A further object is to provide means for controlling the movement of the manually operated mechanism whereby said mechanism will be required to move a predetermined distance before the same can be again operated.

A further object is to provide a coin controlled mechanism for controlling the operation of the pump operating mechanism.

25 30 And a further object is to provide means for disassociating the coin controlled mechanism from the manually operated portion of the pump mechanism.

Other objects and advantages will be 35 hereinafter set forth and more particularly pointed out in the accompanying specification.

In the accompanying drawings which are made a part of this application,

40 Figure 1 is an elevation partly in section of the pump operating mechanism.

Fig. 2 is a sectional view as seen on line 2-2 of Fig. 1.

Fig. 3 is an enlarged sectional view as 45 seen on line 3-3 of Fig. 1.

Fig. 4 is a detail sectional view as seen on line 4-4 of Fig. 1.

Fig. 5 is a top plan view of the coin controlled mechanism for regulating the operation 50 of the pump mechanism.

Fig. 6 is an edge elevation thereof showing one position in full lines and another position in dotted lines.

Fig. 7 is a longitudinal sectional view 55 thereof in operative position, and

Fig. 8 is a longitudinal sectional view

partly broken away, showing the manner of locking the tilting portion of the coin operated mechanism when in proper position to operate.

60

Referring to the drawings in which similar reference numerals designate corresponding parts throughout the several views, 1 indicates a pump cylinder which may be constructed in the usual, or any preferred manner, 2 a discharge pipe from said cylinder, and 3 indicates a rod employed for operating the piston (not shown) within the cylinder.

Positioned a distance above the cylinder 70 is a casing or housing 4 in which is positioned a pair of vertically extending bars 5, said bars projecting a distance above the upper end of the casing, the upper portions of said bars being attached to the casing in 75 any suitable manner, as by means of clips 6. Mounted between the bars 5 are racks 7, the upper and lower ends of said racks being connected together by head blocks 8, said head blocks being preferably mortised out 80 at their ends for the reception of the bars 5 to form guides for the racks. Attached to the upper end of the rod 3 is a platform 9, said platform having recesses 10 which fit around the racks 7, said platform also having guide blocks 11 at its ends which overlap the toothed edges of the racks 7.

Extending transversely through the blocks 11 is a shaft 12 upon which are mounted a pair of gears 13, said gears meshing with the 90 teeth of the racks 7 so that when said shaft 12 is rotated, the platform 9 and the rod 3 attached thereto will be elevated to force the contents of the cylinder 1 through the discharge pipe 2, the shaft 12 being preferably 95 manually operated by means of a crank 14.

The shaft 12 and gears 13 are held against reverse rotation by keying a ratchet wheel 15 to the shaft 12 with which co-operates a pawl 16 mounted within the housing 17 surrounding the ratchet wheel so that when rotating motion is imparted to the shaft 12, it will be necessary to move the same its full distance upwardly before the platform and pump rod can be again lowered.

105

In order to release the gears 13 from the racks 7 to permit the platform 9 and rod 3 to descend after it has reached the upper end of the racks, the gears 13 are splined upon the shaft 12 so that said gears may move inwardly to disengage from the racks, and in order to automatically operate said gears

110

and release them from the racks, a pair of levers 18 are pivotally mounted on the platform 9, one end of the levers being coupled to the hubs of the gears 13, while the opposite ends thereof rest in the path of a substantially V-shaped trip 19 attached to the upper head block 8, said trip being so positioned that the free ends of the levers 18 will be forced apart and the gears 13 moved inwardly on the shaft until they are disengaged from the racks 7, when the platform and parts attached thereto will descend by gravity. In order to return the gears 13 into engagement with the racks 7 after the platform 9 has reached its lowermost position, a pair of trip arms 20 are mounted upon the upper end of the casing 4 and in such position as to engage the free ends of the levers 18 and move said free ends toward each other, thereby forcing the gears 13 outwardly on the shaft 12 and into engagement with the racks 7.

In order to obviate the necessity of measuring the liquid after it is forced from the cylinder, I have provided means for regulating the exact amount of liquid discharged with each operation of the pump rod, comprising the provision of an elongated slot 21 extending longitudinally through each of the racks 7, through which project bolts 22, said bolts also extending through the projecting portions of the bars 5, and by moving the racks upwardly or downwardly upon the bars 5 the amount of liquid discharged with each operation of the rod 3 may be accurately regulated.

In order that a customer may obtain a predetermined amount of the gasoline without requiring the presence of an attendant, I have provided a coin controlled mechanism which will enable the customer to operate the pump mechanism by depositing a proper coin, and to this end, a frame 23 is positioned within the casing 4 upon which is pivotally mounted a tilting platform 24, said platform having a longitudinally extending channel 25 for the reception of a plunger 26, said channel also receiving a coin 27 when deposited at the proper place upon the platform. The platform 24 is provided with a counter balance 28 so that the platform may be adjusted to receive coins of different sizes and weights and caused to properly balance when the required coin has been deposited upon the end of the platform.

In order to hold the rod 3 against operation until such time as the required coin is placed upon the platform, a latch 29 is slidably mounted upon the bars 5, the end of the latch being adapted to engage a notch 30 in the rod 3, said latch being normally held seated in the notch by means of a spring 31. Attached to the outer end of the latch 29 is a cable 32, said cable passing below a sheave 33 and engaged with the pull

rod 34, said rod extending vertically through guides 35 within the casing 4 and through the upper end of the casing, a hand hold 36 being attached to the upper end of the pull rod whereby an upward pull may be readily given said rod. In addition to the spring 31 for moving the latch inwardly, a spring 37 is provided in connection with the pull rod 34 for lowering said pull rod after the same has been elevated.

In order to prevent the rod 34 from being operated until the proper coin has been deposited upon the platform 24, a locking dog 38 is pivotally mounted interiorly of the casing 4, one end of which is adapted to engage a shoulder 39 on the pull rod 34, and the opposite end a shoulder 40, a distance above the shoulder 39 and in reverse position to said latter shoulder, the dog 38 serving to hold the rod 34 in elevated position and the latch 29 out of engagement with the notch 30 when the upper end of the dog is in engagement with the shoulder 40, thereby permitting the pump mechanism to be manually controlled without depositing the coin.

The locking dog 38 is disengaged from the shoulder 39 through the medium of the coin 27 being forced against a lever 41, through the medium of the plunger 26, one end of the lever 41 being pivotally mounted in proximity to the channel 25, while the opposite end thereof normally projects into the channel 25 and is attached to a link 42, said link being in turn attached to the upper end of the locking dog 38, and as said locking dog is pivoted at its longitudinal center, the outward movement of the free end of the lever 41 will swing the locking dog upon its pivot and disengage the lower end thereof from the shoulder 39, thus permitting the pull rod 24 to be elevated. In order to prevent the latch 29 from immediately returning into the notch 30 after an upward pull has been made upon the rod 34, a guard 43 is slidably mounted upon the rod 3 in such position as to immediately descend and cover the notch 30 as soon as the latch 29 has been moved outwardly its full distance so that should the pull rod 34 be released before the rod 3 is moved upwardly, the end of the latch 29 will abut against the guard 43 instead of entering the notch 30.

The plunger 26 is manually operated by extending the handle 44 upwardly through the upper end of the casing 4 so that when the coin has been deposited upon the platform 24 and the channel 25 brought into registration with the plunger, said plunger is moved lengthwise into the channel by grasping the handle 44 and directing pressure thereagainst. Simultaneously with the movement of the coin into the channel 25 by the plunger, a locking rod 45 attached to the plunger 26 is moved lengthwise through eyes 46 and into an opening 47 in the end wall 48

of the frame 23, thereby holding the platform 24 in rigid position until the coin has been moved inwardly its full distance and the plunger 26 again returned to its initial 5 position.

The locking rod 45 is formed of a light 10 resilient substance and one of the eyes 46 is attached to the platform 24 so that should a metallic substance of a greater weight than the coin required to balance the platform be placed upon the platform, the end of the platform to which the eye 46 is attached will be swung above a horizontal plane, thus disposing the free end of the locking rod out 15 of registration with the opening 47 so that when an attempt is made to move the plunger inwardly, the end of the locking rod 45 will engage the solid portion of the end wall 48 and prevent the operation of the plunger 20 26. The normal position of the platform 24 is shown by full lines in Fig. 6 so that when a coin of the proper weight and dimension is placed upon the platform, said platform will be brought to a horizontal position, as shown 25 by dotted lines in Fig. 6, when the plunger may be operated, as previously described. Should the coin be of a less weight than is required to tilt the platform to a perfectly horizontal position, the same action will result 30 as when a coin heavier than is required is placed upon the platform, except that end of the locking rod 45 will engage the end wall 48 below the opening 47.

When an object heavier than the required 35 coin is placed upon the platform, the end of the platform containing the object will tilt downwardly, thus discharging the spurious or overweighted coin through an opening 49 in the frame 23, but a lighter coin or object 40 than that required to properly balance the platform will descend into the channel and pass through an opening 50 in the bottom of the platform 24, and through a registering opening 51 in the frame 23, and when a coin 45 of the proper dimension is forced through the channel 25, it will likewise descend through the openings 50 and 51 into any suitable receptacle provided to receive the same.

50 The link 42, in its passage from the lever 41 to the locking dog 38, passes through a bracket 52, said bracket having an opening 55 through its upper end which is adapted to register with an opening in the link 42 so that by introducing any suitable object through the openings when in registration, the pull rod 34 may be locked in its elevated position by positioning the shoulder 40 above the upper end of the locking dog before the 60 link is moved outwardly and locked in its outward position. As soon as the plunger 26 is returned to its initial position, the lower end of the locking dog 38 is immediately thrown outwardly into the path of the 65 shoulder 39 by means of a spring 53, one end

of which is attached to parts of the casing 4 and the other end to an arm on the locking dog.

It will thus be seen that I have provided a dispensing device which may be used in 70 the ordinary manner or one that can be converted into a coin controlled device, and it will likewise be seen that instead of dispensing the liquid in gallons or fractions thereof that a sufficient amount of the liquid 75 may be dispensed to correspond to the cost thereof in fractions of a dollars, or in other words, if the cost per gallon is more than a fourth of a dollar, the racks 7 may be so set as to dispense an amount slightly less than 80 two gallons, or a sufficient amount to correspond to fifty cents in value, so that by placing a half dollar upon the platform 24, a sufficient amount of the liquid will be dispensed to fully cover the value of the fifty 85 cents.

It will likewise be seen that this device can be readily standardized and applied to the usual form of pump now in general use at a nominal expense, and by properly constructing 90 the various parts, the racks may be quickly adjusted to dispense any amount of the liquid desired.

I claim:—

1. The combination with a pump cylinder 95 and piston rod, of a vertically extending rack bar mounted above said cylinder, a platform connected to said piston rod, a shaft carried by said platform, a gear slidably mounted upon said shaft and rotatable 100 therewith to engage said rack, means to move said gear out of engagement with the rack when the platform is elevated, and means to reengage said gear with the rack 105 when the platform is lowered.

2. The combination with a pump cylinder and piston rod, of vertically extended rack bars mounted above said cylinder, means for adjusting said rack bars, a platform connected to said piston rod, a shaft carried 110 by said platform, gears slidably mounted upon said shaft and rotatable therewith to coöperate with said racks, means at the upper end of said rack bars to shift said gears from engagement with said racks, and means at the lower end of said racks to shift said gears into engagement with said racks. 115

3. The combination with a cylinder and a rod coöoperating with said cylinder, of a pair of spaced bars, a pair of spaced racks 120 between said bars, means to vertically adjust said racks with respect to said bars, a platform attached to the upper end of said rod, a shaft rotatably mounted on said platform, means to rotate said shaft, a pair of 125 gears rotatable with said shaft and slidable thereon, levers attached to said gears, means to disengage said gears from said racks when the platform has reached its upward stroke, and additional means to reengage said gears 130

4
with the racks when the platform has reached its lowermost stroke.

4. In a pumping device of the class described, the combination with a cylinder and a rod coöperating therewith, of a pair of racks, a platform attached to said rod, a shaft rotatably mounted on said platform, means to prevent reverse rotation of said shaft, a pair of gears rotatable with and slidably mounted upon said shaft, said gears meshing with said racks, a lever attached to each gear adapted to move the gears into

and out of engagement with the racks, and tripping mechanisms adapted to operate said levers to move the gears into and out of engagement with said racks. 15

In testimony whereof I have signed my name to this specification in the presence of two subscribing witnesses.

WILLIAM T. HAWKINS.
